(57) **CLAIM**

I claim the ornamental design for a strap of an elbow pad, as shown and described.

DESCRIPTION

FIG. 1 is a perspective view of a strap of an elbow pad according to the present design;

FIG. 2 is a rear elevational view of the strap of an elbow pad of FIG. 1;

FIG. 3 is a front elevational view of the strap of an elbow pad of FIG. 1;

FIG. 4 is a left side elevational view of the strap of an elbow pad of FIG. 1;

FIG. 5 is a right side elevational view of the strap of an elbow pad of FIG. 1;

FIG. 6 is a top plan view of the strap of an elbow pad of FIG. 1; and,

FIG. 7 is a bottom plan view of the strap of an elbow pad of FIG. 1.

The broken lines in the Figures are for illustrative purposes only and form no part of the claimed design.
